Primary Examiner — Susan Moon Lee(74) *Attorney, Agent, or Firm* — Jacobson Holman,
PLLC.(57) **CLAIM**

I claim the ornamental design for a bamboo bird feeder, as shown and described.

DESCRIPTION

The patent file contains at least one drawing executed in color. Copies of this patent with color drawing(s) will be provided by the Patent and Trademark Office upon request and payment of the necessary fee.

FIG. 1 is a side perspective view of a bamboo bird feeder; FIG. 2 is a front perspective view thereof;

FIG. 3 is an interior perspective view thereof;

FIG. 4 is a front elevation view thereof;

FIG. 5 is a side view thereof;

FIG. 6 is a rear elevation view thereof; and,

FIG. 7 is a back perspective view thereof.

Colored drawings are the only practicable medium for illustrating the claimed invention.
